UNITED STATES PATENT OFFICE

96,409

DESIGN FOR AN AUTOMOBILE BONNET

Clyde R. Paton, Birmingham, Mich., assignor to
Packard Motor Car Company, Detroit, Mich.,
a corporation of Michigan

Application June 20, 1934, Serial No. 52,254

Term of patent 3½ years

To all whom it may concern:

Be it known that I, Clyde R. Paton, a citizen of the United States, residing in Birmingham, county of Oakland, State of Michigan, have invented a new, original, and ornamental Design for Automobile Bonnets, of which the following is a specification, reference being had to the accompanying drawing forming a part thereof, and in which:

Fig. 1 is a side view of an automobile bonnet incorporating my new design;

Fig. 2 is an enlarged view of the louvered portion of the automobile bonnet; and

Fig. 3 is a front elevational view of the louvered portion of the automobile bonnet.

The design of the louver, as here shown, is the dominating feature of the design.

I claim:

The ornamental design for an automobile bonnet, as shown and described.

CLYDE R. PATON.
